Primary Examiner—Jennifer Rivard(74) Attorney, Agent, or Firm—Michael E. Dergosits; Samuel S. Lee(57) CLAIM

The ornamental design for a cosmetic block, as shown and described.

DESCRIPTION

FIG. 1 is a top plan view of a cosmetic block showing my new design;

FIG. 2 is perspective view of FIG. 1;

FIG. 3 is a side view of FIG. 1;

FIG. 4 is a top plan view of a second embodiment of FIG. 1, the difference being the configuration of the lettering;

FIG. 5 is perspective view of FIG. 4; and,

FIG. 6 is a side view of FIG. 4.

The bottom plan view of the cosmetic block for each of these embodiments is a flat unornamented surface. The container shown in broken lines in each of these drawings is for illustrative purposes and forms no part of the claimed design.
